CLOCK

Max E. Schlenker, Peru, Ill., assignor to General
Time Corporation, New York, N. Y., a corpora-
tion of Delaware

Application September 8, 1949, Serial No. 4,910

Term of patent 14 years

(Cl. D42—7)

To all whom it may concern:

Be it known that I, Max E. Schlenker, a citizen of the United States, residing at Peru, in the county of La Salle and State of Illinois, have invented a new, original, and ornamental Design for a Clock, of which the following is a specification, reference being had to the accompanying drawing, forming a part thereof.

Figure 1 is a perspective view of a clock, showing my new design, the numerals seen through the elongated slot being merely representative and the small portion of the ornamentation shown being carried over all parts of the clock except the bottom thereof.

Figure 2 is a side elevational view of said clock.

Figure 3 is a top plan view of said clock shown on a reduced scale.

I claim:

The ornamental design for a clock, substan-
tially as shown and described.

MAX E. SCHLENKER.
